CLAIM

The ornamental Design for an upper body garment, as shown.

DESCRIPTION

FIG. 1 is a perspective view of an upper body garment in accordance with my Design;

FIG. 2 is a front elevational view;

FIG. 3 is a top plan view;

FIG. 4 is a bottom plan view;

FIG. 5 is a rear elevational view;

FIG. 6 is an elevational view from the left in FIG. 2; the elevational view from the right is a mirror image of FIG. 6; and,

FIG. 7 is a view similar to FIG. 1 but shaded to show contrasting colours between the over collar and the under collar elements of the garment.

The broken lines in the drawings denote parts of the article that are not part of the design and that may vary.
